F. A. HOWARD,
STORAGE OF LIQUIDS.
FILED APR. 12, 1920.

20 Inventor.
Frank A. Howard,
Brooklyn, N. Y., citizen of the
State of New York.

UNITED STATES PATENT OFFICE.

FRANK A. HOWARD, OF WESTFIELD, NEW JERSEY, ASSIGNOR, BY MESNE ASSIGNMENTS, TO STANDARD DEVELOPMENT COMPANY, A CORPORATION OF DELAWARE.

STORAGE OF LIQUIDS.

Application filed April 12, 1920. Serial No. 373,094.

To all whom it may concern:

Be it known that I, FRANK A. HOWARD, a citizen of the United States, residing at Westfield, in the county of Union and State 5 of New Jersey, have invented a new and useful Improvement in the Storage of Liquids, of which the following is a specification.

The present invention relates to the storage of liquids, and more particularly to the storage of volatile or inflammable liquids, in closed tanks completely filled with liquid. It will be clearly understood from the following specification, as illustrated by the 15 accompanying drawing, in which—

Figure 1 is a sectional view through a tank suitable for use in connection with the present invention.

Figure 2 is a sectional detail view of an 20 element in the tank.

In the drawings the numeral 5 indicates a storage tank intended to be filled with a volatile or inflammable liquid, such as gasoline. The tank is provided with the 25 usual swing pipe 6 for the inlet and removal of the gasoline, and with a vent pipe 7 provided near the top of the tank with a valve 8. A vertical stand pipe 9 is mounted within the tank, preferably on an expanded base 10, and its interior communicates with the tank near the bottom of the latter, as thru openings 11 in the base 10. The top of the standpipe 9 extends above the top of the tank 5 and may be closed by 30 a cap 12. Means are provided for introducing liquid into the stand pipe 9, for example, valved pipe 13. If desired, means may likewise be provided above the top of the tank 5 for discharge or overflow of 35 liquid, as through valved pipe 14. A waste or discharge pipe 15 extends vertically into the stand pipe 9, and to the top of this is attached an externally threaded brass ring 16. A pipe section 17, closed at the top, 40 screws over the ring and may be vertically adjusted, for example, by means of the stem or shaft 18, splined in the hub of hand wheel 19, the construction of which is not shown in detail, being identical with that of 45 the ordinary rising-stem gate-valve. The pipe section is provided with horizontal slots or openings 21, through which liquid may pass from the stand pipe 9 into waste pipe 15.

50 In carrying out the present invention the

tank 5 is, it is assumed, filled with the stored liquid, for example, gasoline, up to the usual limit, i. e. leaving enough space for the expansion of the liquid under the contemplated maximum increase of the temperature. 60 A heavier, immiscible liquid, such as water, is then caused to enter the stand pipe 9, forming a layer on the bottom of the tank and forcing the gasoline up to the top of the tank, the valve 8 on the vent pipe being 65 open during the filling process. The level of the water is indicated by the numeral 20 on the drawing. It is intended that the pressure which the gasoline exerts upon the roof or top of the tank shall not exceed a 70 maximum, and this may be effected by adjusting the level of the column of water or liquid in the stand pipe 9 to counterbalance the gasoline. The liquid in the stand pipe overflows through openings 21 into waste 75 pipe 15, and the height of the column of liquid may be raised or lowered by raising or lowering the pipe or cap section 17. In order that contraction of the stored liquid for example, with changes in temperature, 80 may be compensated for, water will be constantly supplied through the pipe 13, the rate of supply of water to the stand pipe being greater than the rate of volumetric contraction of the liquid in the tank, and 85 the excess discharging through the overflow, thru which also discharges any liquid expelled by expansion of the contents of the tank. The column of water in the stand pipe may be regarded as functioning to 90 produce a substantially constant pressure against the roof of the tank, which pressure would cause the gasoline to reach a level slightly above the top of the tank if the liquid were free. This level will show in 95 the vent pipe 7 if the latter be kept open. The roof supports 23 serve also to tie the roof against upward pressure from the contents of the tank.

100 A suitable gauge 22 may be provided indicating the level of gasoline in the tank, this gauge being shown as an annulus of specific gravity intermediate between that of water and of gasoline. To make the necessary external connections for this gauge as 105 well as for the swing pipe 6 tubes are extended downward through the roof of the tank, these tubes housing the connecting cables. In this manner the cables may be run through the roof without danger of

leakage, and, furthermore, since the tubes extend nearly to the bottom of the tank they are filled with water and not gasoline.

In case it is desired to counterbalance the gasoline or liquid in the tank with the same liquid instead of with water, the cap section 17 may be screwed down until the slots 21 are closed, or the waste line 15 may be closed by a valve conveniently located (not shown) and the overflow pipe 14 may be opened. This pipe is placed at a point above the level of the roof of the tank, the hydrostatic pressure upon the roof of the tank being measured by the difference between the overflow level and roof of the tank. Gasoline may then be supplied thru pipe 13 at a rate greater than the rate of volumetric contraction of the liquid in the tank with decreases in temperature, the excess passing out through the overflow 14. This excess will be collected, and if desired, returned through the pipe 13, a circulating system being employed to take care of a number of tanks. In this mode of operation there may be liquid communication thru the wall of stand-pipe 9 at any point within the tank, or that portion within the tank may be entirely eliminated, if desired.

It is apparent that, in accordance with the present invention the pressure exerted by the contents of the tank upon its roof may be readily controlled. In the storage of liquids, and particularly of volatile or inflammable liquids it is desirable that the tanks be completely filled and that vapor spaces in the tank be avoided. It is hence important that the hydrostatic pressure on the liquid be always sufficient to keep the tank entirely full. By the present invention this object is attained and at the same time the tank may be protected against excessive pressure dangerous to the structure of the tank itself.

What I claim as new and desire to secure by Letters Patent is:—

1. The method of maintaining a constant hydrostatic head of a stored liquid subjected to changes of temperature which consists in balancing it against a column of liquid, constantly supplying liquid to the column at a rate greater than the rate of volumetric contraction of the contents with changes of temperature and wasting the excess liquid as well as the expelled liquid through a constant level overflow.

2. The method of protecting a completely filled storage tank against excessive pressures due to the expansion and contraction of its contents, which consists in constantly supplying liquid to the interior of the tank at a rate greater than the rate of volumetric contraction of the contents with changes in temperature and wasting the excess liquid as well as the expelled liquid thru a constant level overflow.

3. The method of protecting a completely filled storage tank against excessive pressures due to the expansion and contraction of its contents, which consists in balancing the contents against a column of liquid, constantly supplying liquid to said column at a rate greater than the rate of volumetric contraction of the contents with changes in temperature and wasting the excess liquid as well as the expelled liquid through a constant level overflow.

4. The method of protecting a completely filled storage tank against excessive pressures due to the expansion and contraction of its contents, which consists in maintaining a column of liquid immiscible with and heavier than the stored liquid in hydraulic communication with the lower portion of the tank, constantly supplying liquid to said column at a rate greater than the rate of volumetric contraction of the contents with changes in temperature and wasting the excess liquid as well as the expelled liquid thru a constant level overflow.

5. The method of protecting a completely filled gasoline storage tank against excessive internal pressures which consists in maintaining a column of water in hydraulic communication with the lower portion of the tank, constantly supplying water to said columns at a rate greater than the rate of volumetric contraction of the gasoline in the tank with changes in temperature and wasting the excess of water as well as expelled water thru a constant level overflow.

6. The combination with a closed storage tank, of a stand pipe within the tank and communicating with the latter at or near the bottom, means for introducing liquid into the standpipe at a rate in excess of the rate of volumetric contraction of the stored liquid, a waste pipe within the stand pipe, a vertically movable cap for said waste pipe, said cap being provided with an opening for communication of the interior of the stand pipe with the waste pipe whereby liquid may be wasted from the latter.

7. The combination with a closed storage tank, of a stand pipe within the tank and communicating with the latter at or near the bottom, means for introducing a liquid heavier than the stored liquid into the stand pipe at a rate in excess of the rate of volumetric contraction of the stored liquid, a waste pipe within the stand pipe, a vertically movable cap for said waste pipe, said cap being provided with an opening for communication of the interior of the stand pipe with the waste pipe, said opening being at a height somewhat above that necessary to counterbalance the head of liquid in the tank when the latter is filled, the excess of liquid being wasted from the stand pipe.

8. The combination with a closed storage

- tank, of a stand pipe communicating with the latter at or near the bottom, means for introducing liquid into the stand pipe at a rate in excess of the rate of volumetric con-
5 traction of the stored liquid, overflow means cooperating with the standpipe to waste therefrom liquid in excess of that necessary to maintain a determined hydrostatic head of liquid in the tank and means for varying
10 the vertical position of said overflow means.
9. The combination with a closed storage
- tank, of a stand-pipe communicating with the tank at or near its bottom, means for introducing the liquid into the stand-pipe, a waste-pipe within the stand-pipe, said 15 waste-pipe being provided with an opening for communication between the interior of the waste-pipe and the interior of the stand-pipe, and means for varying the vertical position of the opening.

FRANK A. HOWARD.
